UNITED STATES PATENT OFFICE.

VICTOR E. LOMBARD, OF BLUEFIELD, WEST VIRGINIA.

SMOKE SEPARATOR.

Application filed June 15, 1922. Serial No. 568,491.

This invention relates to apparatus for conserving valuable ingredients from smoke and has for an object to provide improved means for passing the smoke in a downward direction through a chamber containing a plurality of elements coated with water so that the smoke in passing comes in contact with the water film and the valuable ingredients contained in the smoke, especially in the way of water-soluble chemicals, are dissolved and pass outwardly with the water for further processing and conserving.

A further object of the invention is to provide, in combination with a smoke exit or flue, a chamber having a plurality of elements, such for instance as chains so positioned therein as to make it necessary for smoke passing from the flue to the outlet of the chamber to pass through and over, about and among, the chains which are constantly kept wet with water upon their exterior surfaces to form an aqueous film which film drips into a receptacle carrying therewith the water-soluble ingredients of the smoke to be again used for like purposes until the water is saturated or until for any reason it is found desirable to discharge the water from the receptacle.

A further object of the invention is to provide a device of the class which is so proportioned that it may be employed upon a locomotive of substantially the usual and ordinary type resulting in delivering from the locomotive smoke not only free from sparks, but discharged of its water-soluble chemical ingredients, which ingredients are conserved or are simply dumped, wherein the utility of the device is to prevent the emission of sparks and black smoke.

With these and other objects in view the invention comprises certain novel parts, elements, units, constructions, combinations, inter-actions and functions, as disclosed in the drawings together with mechanical equivalents thereof as will be hereinafter more fully described and claimed.

In the drawings:

Figure 1 is a view in vertical section of one embodiment of the present invention of the type preferably adapted to use in combination with a stationary installation, although showing a type which may also

be installed upon a portable installation such as a locomotive;

Figure 2 is a vertical sectional view taken at right angles to Figure 1, as indicated by line 2-2 at Figure 1;

Figure 3 is a transverse sectional view taken on a horizontal plane, as indicated by line 3-3 of Figure 1;

Figure 4 is an enlarged detail sectional view of the manner of attaching the chains to the water-supply nozzles.

Like characters of reference indicate corresponding parts throughout the several views.

The type of device which forms the subject matter of this application and which is intended more particularly for attachment to and association with stationary installations as represented diagrammatically by the stack 10 at Figure 1, with a damper 11 for forming direct draft through said stack or diverting it through the passage 12 which forms the initial introduction to and connection with the present invention, and has a diameter greater than the stack 10.

The invention comprises a housing for convenience preferably composed of the upper section 13 and lower section 14, although it is obvious that this housing may be formed integral.

At the top of the housing a chamber 15 is provided having a plurality of pipes 16 located therein with laterally-extending nipples or nozzles 17. From these nipples or nozzles 17 depend a like number of chains 18, the chains being of such relative lengths and proportions that at the side of the chamber opposite the inlet 12 the chains substantially disappear and at the side of the conduit 12 extend downwardly and completely cover this inlet opening, as indicated more particularly at Figure 1.

Within this housing a frame 19 is secured in any approved manner, as by the bolts 20. Between the opposite sides of the frame 19 a plurality of chains 21 are suspended on an inclined plane, the lower end of the upper series or plane of chains being below the lowermost limits of the inlet conduit 12 and the upper end extending substantially to the top of the housing 13, so that the outlet port 22, which is located considerably below the

inlet conduit 12 necessitates the passage of the smoke or products of combustion from the inlet passage 12 through the several chains 18 and 21 in passing from such inlet conduit 12 to the outlet port 22.

The chains 18 are kept continuously wetted with a film of water which is supplied to the pipes 16 by means of an inflow pipe 23 from a pump 24. The chains 18 being located directly above the chains 21, the water supplied to the chains 18 in addition to forming a film of water continuously upon the exterior of such chains drips down to and upon the chains 21 where it also forms continuously a film of water which finally drips downwardly into a funnel 25 located in the housing. Preferably this funnel is secured in the housing by means of a flange 26 secured between the sections 13 and 14 of the housing, but it is obvious that any other manner of securing the funnel in such housing will be within the scope of the present invention. The funnel 25 communicates by means of a pipe 27, preferably, though not necessarily tapered with a goose-neck 28 which discharges into a closed box or receptacle 29. This box or receptacle 29 communicates by means of a pipe 30 with the pump 24 so that the pump 24 takes its supply from said receptacle 29, conveying it through the pipe 23 to the pipe 16, and discharges it upon the chain as hereinbefore described, from which it drips down through the funnel 25 and pipe 27 to return to the receptacle 29. As the smoke from the stack 10 through the inlet conduit 12 usually is in a considerably heated condition, it is obvious that a certain proportion of the water upon the chains will be evaporated and will pass outwardly through the exhaust port 22. For maintaining sufficient supply of water in the receptacle 29 to at all times accomplish the purpose, an inlet pipe 31 from any convenient source of water supply leads into the auxiliary chamber 32. The inlet pipe 31 is controlled by a float valve of any usual and ordinary construction whereby a constant water level is maintained and a passage 33 forms communication between the auxiliary chamber 32 and the chamber 29 for maintaining the water level in the latter chamber. The partition which is provided with the passage 33 prevents agitation in the chamber 29 which might be caused by the inflow of water from the inlet pipe 31 so that the water in the chamber 29 is maintained substantially still.

For the purpose of discharging the fluid containing soluble chemicals of the receptacle 29 a valved-discharge pipe 34 is provided. As shown at Figure 1, a pipe 35 is employed simply to carry the exhaust from the pump 24 to the housing where it passes through the housing the same as the smoke from the stack 10.

It is within the present scope of the invention and is only necessary that the chains 18 be suspended from nipples 17 which communicate with the pipe 16, but preferably these nipples 17 will have tapered extremities, as shown at 36 in Figure 4, so that there is an attenuated and annular orifice between the shank 37 to which the chain is attached, and the inner periphery of the tapered extremity 36 discharging therefore a very small quantity of water relatively about the shank 37 to drip down upon the chain 18. This may be secured in the nipple also in any approved manner, but preferably by forming an eye 38 upon the shank 37 and employing a wire or rod 39 which may be a short wire to operate only independently for each of the chain installations or a rod extending the entire length of the pipe 16 and engaging a number of these eyes 38 upon the same number of chains. At Figure 4 the wire 39 is shown broken to indicate that it is of indeterminate length and may be as stated merely for securing a single unit in place, or may extend the entire length of the pipe 16.

It is obvious that the contact of the smoke passing through the inlet pipe 12 and into engagement with the wetted chains 18 and 21 will cool the smoke very rapidly, thereby reducing the volume and aside from the draft caused by the smoke passing out through the exhaust port 22 would produce a draft in the pipe 16.

It is obvious that the water passing outwardly among the chains and through the chamber will carry with it some insoluble gases and smoke which will be introduced with the water into the receptacle 29. So that these insoluble or fixed gases may escape, a pipe 40 is located in the pipe 27 and spaced therefrom by any approved type of spacers conventionally or diagrammatically shown at Figure 1, it being understood that the particular type of spacer is immaterial, so that it forms a substantially annular passage between the pipes 27 and 40 through which the water flow into the funnel 25 may pass through the goose-neck 28 to the receptacle. A conical baffle 42 is placed over the top of this pipe 40 so that the drip from the chain will not pass into or through the pipe 40 but will be diverted into the funnel 25 to pass through the pipe 27 about the pipe 40 permitting uncondensed smoke or fixed gases to rise through this pipe 40 to be again acted upon by the water or to pass outwardly through the discharge port 22.

Throughout the description and in the claims of this application the term water has been used as the liquid employed for dissolving the ingredients or wetting the particles, but it is to be understood that the invention is in no way limited to the use of pure water or relatively pure water and that

any liquid or solution will be fully within the terms of the present invention, such solution or liquid depending upon the nature of the products of combustion which enter the apparatus and the materials which it is especially desirable to extract from such products.

What I claim is:

1. An apparatus for extracting chemical ingredients from smoke comprising a chamber having an inlet opening communicating with a smoke flue and an outlet opening lower than the inlet opening, a plurality of chains suspended in the chamber some of said chains positioned vertically covering the inlet opening and others inclined at an angle to the vertical and covering the outlet opening, means to supply water to maintain an aqueous film upon the chains, a receptacle below the chains to receive the drip from the chains, and a pump to return the drip from the receptacle to again moisten the chains.

2. An apparatus for extracting the chemical ingredients of smoke comprising a chamber having an inlet passage in communication with a smoke flue and an outlet port lower than the inlet passage, a plurality of chains suspended vertically from the top of the chamber and covering the inlet passage, nozzles positioned to discharge water upon the several suspended chains, a receptacle

disposed below the chains in position to receive drip therefrom, a pump communicating at one side with the receptacle and at its opposite side with the nozzles and adapted to discharge through the nozzles water to maintain an aqueous film upon the chains, and means to maintain a substantially constant water level in the receptacle.

3. An apparatus for extracting chemical ingredients from smoke comprising a chamber having a plurality of chains suspended vertically from the top wall of said chamber, a series of chains below said first-mentioned chains and disposed at an inclination to the axes of said first-mentioned chains, an inlet conduit communicating with the chamber and covered by the vertical series of chains, an outlet structure including a port communicating with said chamber below said vertical chains, nozzles positioned to discharge water upon the vertical chains, a pump for supplying water to the nozzles, a receptacle positioned to receive the drip from the chains and communicating with the pump, means to maintain a substantially constant water level in the receptacle, and means for discharging the resultant solution from the receptacle.

In testimony whereof I hereunto affix my signature.

VICTOR E. LOMBARD.
